UNITED STATES PATENT OFFICE

EDWARD A. RUSSELL AND JOHN VAN VULPEN, OF CHICAGO, ILLINOIS, ASSIGNOR TO
VAPOR CAR HEATING COMPANY, INC., OF CHICAGO, ILLINOIS, A CORPORATION OF
NEW YORK

VAPOR CAR HEATING SYSTEM

Application filed April 7, 1930. Serial No. 442,181.

This invention relates to certain new and useful improvements in vapor car heating systems and more particularly to an improved type of radiating system mounted in and concealed by the side walls of the railway car.

In order to improve the appearance of the car, economize on space, and provide greater efficiency in the heating system, it is desirable that the radiating system be mounted within the hollow walls of the car, or partially within these walls, rather than in the open body of the car as in systems heretofore in use. The ordinary side wall construction of passenger cars comprises a plurality of spaced apart vertical posts which carry the inner and outer walls, that is the inner lining wall and the outer car sheathing. Separated spaces are thus provided between the pairs of posts and the inner and outer walls. These spaces provide ample room for the radiating coils or pipes and the reflecting shields and insulation associated therewith. However, it is desirable that continuous pipe coils extending longitudinally of the car be used, and the ordinary form of vertical posts used in the car wall construction stand in the way of these pipes. According to the present invention, the lower portions of these posts are cut away on their inner sides so as to provide a shallow passage extending longitudinally of the car near the floor through which the radiating pipes may pass. Preferably the posts are flattened out at their lower ends so as to stand back out of contact with the inner side wall, the reduced thickness of the post being compensated for by an increase in breadth so that the necessary strength is not sacrificed. The longitudinally extending pipes or coils are supported directly on the inner faces of these flattened portions of the post by means of suitable clamps or brackets. In the spaces between the posts, radiating fins may be mounted on the pipes so as to increase the radiating surface, and reflecting shields are positioned behind the coils so as to prevent heat losses and cooperate with inlet and outlet passages in the inner side wall of the car

to provide a circulation around the heating coils.

The principal object of this invention is to provide an improved concealed radiating system for railway cars, such as is briefly described hereinabove and is disclosed more in detail in the description to follow.

Another object is to provide an improved form of concealed radiator for use in the walls of railway cars.

Another object is to provide an improved form of side wall construction for railway cars to permit the use of concealed radiating systems therein.

Other objects and advantages of this invention will be more apparent from the following detailed description of one approved form of heating system embodying the principles of this invention.

In the accompanying drawings:

Fig. 1 is a side elevation of a portion of the inner side wall of a railway car, partially broken away, the floor of the car being shown in vertical section.

Fig. 2 is a similar view showing a modified form of radiating coil.

Fig. 3 is an enlarged vertical section taken substantially on the line 3-3 of Fig. 1.

Fig. 4 is an enlarged vertical section taken substantially on the line 4-4 of Fig. 1.

Fig. 5 is a detail vertical section taken substantially on the line 5-5 of Fig. 3.

Fig. 6 is a horizontal section taken substantially on the line 6-6 of Fig. 5.

A portion of one side wall of the car is indicated at A, and a portion of the floor at B. The side wall comprises a plurality of vertical posts C spaced apart longitudinally of the car, and the inner wall D and the outer wall E carried by these posts C. Windows F are provided between the upper portions of the posts C, or between certain of the pairs of posts, leaving spaces G beneath the several windows which are separated from one another and inclosed by the adjacent pair of posts C and the inner and outer walls D and E. It is in these several wall spaces G that the major portions of the radiating system is positioned.

The posts C may take a variety of forms,

but are preferably constructed of a pair of channel beams 1 and 2 connected by suitable covering plates such as 3 and 4. In their normal form, as exemplified in the upper portions of the posts C in the present disclosure, these posts are relatively narrow (in the direction longitudinally of the car) and are of sufficient depth to extend between the inner and outer walls D and E which the posts contact with and support. According to the present invention, the lower portions of these posts are flattened outwardly on their inner sides, that is made of less depth and greater width (as shown at 5 in Figs. 3 and 4), so as to leave a shallow vertical space extending longitudinally of the car between the front faces of the posts and the inner wall D, this space being sufficiently deep to accommodate the radiating pipes 6 which extend continuously throughout a considerable portion of the length of the car. These pipes 6 are mounted against and secured to the front faces of the flattened portions 5 of the posts by any suitable means such as the straps or brackets 7 and bolts 8 illustrated in the drawings.

A plurality of radiating fins 9 may be secured on the pipes 6, in the wall spaces G between the posts, in order to increase the radiating surface. A reflecting shield 10 is positioned in each wall space G behind the radiating coils, a lower horizontal portion 11 of this shield extending beneath the coils and being anchored at 12 to the lower portion of the inner wall D adjacent the floor B, and the upper portion of the shield curving inwardly and upwardly at 13 and being anchored at 14 to the inner wall D above the radiators. Each portion of the inner wall D in front of one of these shields 10 is provided with an inlet passage or opening 15 beneath the radiator, and an outlet passage or opening 16 above the radiator so as to permit a free circulation of air from the interior of the car, around and between the heating coils, as indicated by the arrows in Fig. 3. If necessary, the lower portion of the inner wall D may be bowed inwardly as indicated at 17 to provide sufficient space between the inner wall and the heating coils for the passage of the air currents. Preferably, the upper outlet opening 16 will be covered by a suitable grill as indicated at 18, so as to partially close this opening without interfering with the circulation of air therethrough. Suitable insulation, as indicated at 19, may be provided behind and around the shields 10, as may be found necessary or desirable in order to protect the walls of the car and prevent heat losses.

Although this radiating system might be utilized with different types of heating systems, it is particularly designed for use in a vapor car heating system of well known

type, two examples of which are rather diagrammatically illustrated in the drawings. In the simpler system shown in Fig. 2 live steam from the main train line 20 passes through pipe 21 to the vapor regulator 22 which controls the flow of steam at reduced pressure through pipe 23 to the distributing valve 24. The steam or vapor flows from distributing valve 24 through pipe 25 to the upper longitudinally extending radiating pipe 6, and the several pipes 6 are successively connected in pairs by couplings 26 at the ends thereof so as to form one continuous pipe coil, the steam and condensate flowing from the lowermost radiating pipe through connecting pipe 27 back to the distributing valve 24 and thence through pipe 28 to the vapor regulator, whereby the steam supply is automatically controlled in well known manner. The distributing valve 24 may be controlled by hand or automatically by thermostats, as is well known in the art. In the modified form of radiating system shown in Fig. 1, the radiating pipes are connected in two series so as to form two separate radiating coils, the two upper pipes 29 and 30 being connected at the end remote from the distributing valves by a coupling 31, and the lower pipes 32 and 33 being similarly connected by a coupling 34. A pair of separate distributing valves 24 and 24' are used, the steam supply being directed to the first distributing valve 24 and thence through the pipes 29 and 30 of the first heating coil and back to the valve 24 as in the first described system shown in Fig. 2. The steam returned from the first coil flows through connecting pipe 35 to the second distributing valve 24' and thence through the second heating coil from which it is returned by pipe 33 to the valve 24' and thence through pipe 28 back to the vapor regulator. By proper control of the distributing valves, one of the heating coils may be cut out of service when a single coil is sufficient to satisfy the heating requirements.

Preferably there will be at least one of these radiating systems in each side wall of the car, and if desired two or more such systems can be arranged end to end in one side wall, in case it becomes undesirable or impractical to further extend the length of the heating coils in any one system.

It will now be apparent that the only change that is necessary in the ordinary construction of the side wall of the car, is the changed conformation of the lower portion of the posts C, and the provision of the necessary circulation passages in the inner wall D. At the same time, radiating coils of ample size to satisfy any maximum heating requirements can easily be installed without materially encroaching on the clear space provided in the interior of the car. This

type of installation is much more sightly than those in which the pipe coils are mounted directly in the car compartment, and the comfort of the passengers is increased and a more efficient circulation of the heated air is provided.

We claim:

1. A concealed radiating system for heating railway cars comprising the combination with the side wall of a car consisting of a plurality of spaced apart vertical posts and the inner and outer walls carried thereby so as to enclose a plurality of separated wall spaces, one between each adjacent pair of posts, the lower inner portions of the posts being flattened outwardly and away from the inner wall so as to provide a shallow vertical channel behind the inner wall and extending longitudinally of the car, of radiating pipe coils consisting of a plurality of parallel pipes extending longitudinally of the car, means for securing the pipes to the lower flattened portions of the posts within the shallow channel, and means mounted on the pipes for increasing the heat-transmitting surface of those portions of the pipes within the wall spaces, the inner wall being provided with openings between the posts to permit circulation of air from within the car through the wall spaces around the radiating coils. 90
2. A concealed radiating system for heating railway cars comprising the combination with the side wall of a car consisting of a plurality of spaced apart vertical posts and the inner and outer walls carried thereby so as to enclose a plurality of separated wall spaces, one between each adjacent pair of posts, the lower inner portions of the posts being flattened outwardly and away from the inner wall so as to provide a shallow vertical channel behind the inner wall and extending longitudinally of the car, of radiating pipe coils consisting of a plurality of parallel pipes extending longitudinally of the car, means for securing the pipes to the lower flattened portions of the posts within the shallow channel, reflecting shields mounted behind the pipes within each of the wall spaces, said shields being secured to the inner wall above and below the pipes and extending back around the pipes in spaced relation thereto so as to provide an air circulation passage behind the pipes, the lower portion of the inner wall being bowed inwardly so as to provide a circulation passage in front of the pipes, said inner wall being provided with inlet and outlet passages below and above the group of pipes in each wall space, and means mounted on those portions of the pipes adjacent the circulation passages to increase the heat transmitting surface of these portions of the pipes. 125
3. A concealed radiating system for heating railway cars comprising the combination with the side walls of a car consisting of a plurality of spaced apart vertical posts and the inner and outer walls carried thereby so as to enclose a plurality of separated wall spaces, one between each adjacent pair of posts, the posts being formed of channel beams and connecting plates and their lower portions being flattened out longitudinally of the car on their inner sides so as to contact with the outer wall but be in spaced relation to the inner wall and provide a shallow vertical channel behind the inner wall and extending longitudinally of the car, of radiating pipe coils consisting of a plurality of parallel pipes extending longitudinally of the car, means for securing the pipes to the lower flattened portions of the posts within the shallow channel, and fins mounted on those portions of the pipes within the wall spaces to increase the heat transmitting surface of these portions of the pipes, the inner wall being provided with openings to permit circulation of air from within the car around the radiating coils. 130
4. A concealed radiating system for heating railway cars comprising the combination with the side wall of a car consisting of a plurality of spaced apart vertical posts and the inner and outer walls carried thereby so as to enclose a plurality of separated wall spaces, one between each adjacent pair of posts, the posts being formed of channel beams and connecting plates and their lower portions being flattened out longitudinally of the car on their inner sides so as to contact with the outer wall but be in spaced relation to the inner wall and provide a shallow vertical channel behind the inner wall and extending longitudinally of the car, of radiating pipe coils consisting of a plurality of parallel pipes extending longitudinally of the car, means for securing the pipes to the lower flattened portions of the posts within the shallow channel, reflecting shields mounted behind the pipes within each of the wall spaces, said shields being secured to the inner wall above and below the pipes and extending back around the pipes in spaced relation thereto so as to provide an air circulation passage behind the pipes, the lower portion of the inner wall being bowed inwardly so as to provide a circulation passage in front of the pipes, said inner wall being provided with inlet and outlet passages below and above the group of pipes in each wall space, and fins mounted on those portions of the pipes adjacent the circulation passages to increase the heat transmitting surface thereof. 135
5. In a vapor car heating system, in combination with means for supplying and regulating the vapor flow, a radiator comprising a pipe-loop extending longitudinally of the car, means for supporting said pipe-loop within a side wall of the car, an inner

wall for concealing the pipe-loop, said inner wall having at intervals inlet and outlet openings arranged in pairs, positioned below and above said radiator, radiating fins mounted on those portions of the pipe-loop which lie between each pair of cooperating inlet and outlet openings and reflecting shields positioned behind said finned portions of said pipe-loop and curved inwardly above said finned portions and anchored to said inner wall above the said outlet openings, so as to direct the heated air through said outlet passages into the car.
